ADVERTISING FOLDER

Robert Stuart, Long Island, N. Y.

Application January 16, 1933, Serial No. 651,994

2 Claims. (Cl. 40—126)

The present invention relates to circular letters, post-card folders or like foldable articles of sheet material characterized by their having an insert or display adapted to lie flat between folds and to stand upright upon opening of said folds. Such devices are used mainly for advertising purposes, as they create an element of surprise due to the fact that the insert is quite invisible before the folder is opened and appears unexpectedly only when the folder is opened, and are therefore helpful in drawing the recipient's attention to the reading or advertising matter on said folder.

An object of the invention is to provide a device of the character described which is simple in construction and reliable in operation, and which can be readily manufactured at very little expense.

A more specific object of the invention is to provide a structure having both folder and insert attached thereto constructed from a single piece of sheet material.

These and other objects and features of the invention will more fully appear with the aid of the following description taken in conjunction with the accompanying drawing in which Fig. 1 is a plan view of a blank; Fig. 2 is a perspective view in unfolded position of the completed device made from said blank; Fig. 3 is a cross sectional view on the plane indicated by the line 3—3 of Fig. 2; and Fig. 4 is an enlarged cross-sectional view of the device in folded position.

The inventive concept is illustrated in the drawing as applied to the making of a circular letter 1 shown in Fig. 2 as comprising, as is generally the custom, three approximately equal areas or folds 2, 3 and 4 separated by the usual creases or score lines 5 and 6 along which the extreme areas may be folded over the central area. The following disclosure will show, however, that the invention is not restricted to this particular embodiment, but may likewise be utilized for making any other foldable article, such as a post-card bent or folded upon itself along a center crease.

In the drawing, I have shown a flat insert or display 7 located at the upper edge and near one marginal edge of the paper blank 9, as shown on Fig. 1, but which, when the advertising folder 1 is completed, extends from the crease 5 thereof, as shown in Fig. 2. As will be hereinafter more particularly described, this display 7 is adapted to lie flat against the area 2 when the letter 1 is folded, but to assume an upright position perpendicular to the plane of the letter 1 upon opening the latter. The display 7 is capa-

ble of various forms or shapes, the particular shape chosen forming no part of the invention. When used for advertising purposes, it may be made symbolic or suggestive of the advertisement or reading matter printed on the upper surface 60 of the letter 1, the point of this printed matter being thus emphasized and the reader amused as well.

In accordance with my invention, I construct the device including the insert or display 7 from the blank 9 cut, as by a die, from a single sheet of paper or other suitable sheet material. I shape this blank to include an additional upper portion 10 over the amount of material necessary to construct the usual letter folds and covering an area 65 equal or substantially equal to that required to construct the upper fold. Thus, in Fig. 1, I have shown the blank 9 as comprising four equal portions 10, 2, 3 and 4, the lower portions 2, 3 and 4 being separated, as above indicated, by the creases 5 and 6 and being adapted to carry the advertising literature on the upper surface thereof. The line 11 separates the upper portion 10 from said lower portions, the paper being creased along this line in such a direction as to permit 70 the blank to be folded back upon itself at said portion 10.

The display 7 extends from the upper edge 12 of the portion 10, and at the same distance from a longitudinal edge of the blank I form at the 75 crease 5 a slit or elongated opening 13 having a length corresponding to or slightly greater than the width of the display 7 at its base. The display 7 is passed through the opening 13 upon folding the portion 10 beneath the portion 2. 80 Since said portions 2 and 10 are of equal areas, they are therefore caused to lie in snug engagement with one another by pasting them together, and the display 7 is caused to extend completely through the slit 13 or the base of said display to 85 be located in said slit. The display is creased at its base along the line 14 in substantial alinement with the upper edge 12 of the blank, either prior to or after insertion of the display through the slit. In the completed article, the crease 14 is 90 located at the slit 12, i. e. in alinement with the crease 5, and is formed in such a direction as to cause the display 7 to project upright or to assume a position transverse to the plane of the portion 2.

In folding the device, the display 7 is preferably caused to lie adjacent the portion 2 of the sheet. Thus, I may first bring the upper fold (comprising the glued portions 2 and 10) and the central fold 3 together and then fold the lower portion 4 100

over said upper fold. This folded position is illustrated in Fig. 4. Or, I may first bring the portions 3 and 4 together and then the display 7 and upper fold over the lower fold 4. No matter 5 in what manner the device is folded, however, the nature of the crease 14 will cause the display 7 to stand upright upon unfolding the device from its folded position.

If desired, the blank 9 may be provided with a 10 cut-out portion or tab 15 extending from the display portion 7 of said blank. The free end 16 of this tab is glued or otherwise secured to either the surface 2 or the surface 3, but preferably to the surface 3, as illustrated in Figs. 2 and 3, such 15 tab acting as a prop for the display 7, as well as assisting the display to assume an upright position, when the letter is unfolded. When folding the letter, the tab 15 will crease along one or several lines, such as the line 17, intermediate 20 its attached ends.

A number of tabs or props may be utilized in the same manner. For example, one tab may be secured to the surface 3 and another to the surface 2. As illustrated in the drawing, such tab 25 or tabs may be made an intrinsic part of the figure or object which is to be simulated or displayed. It is desired to be understood, however, that the prop is unessential in so far as the operation or raising of the display is concerned, that 30 is the main display portion 7 tends to assume an upright position by reason of its proper construction. This I consider an important feature of my invention.

When the tab or tabs are secured to the surface 3, it is essential that, in folding the device, the surface 2 be brought to lie adjacent the surface 3, as illustrated in Fig. 4.

It now becomes apparent that I have provided an advertising folder which is efficient, yet inexpensive to manufacture, and one which will hold the reader's interest.

What is claimed is:

1. A device of the character described comprising a blank of sheet material having a crease dividing it into an upper and a lower fold and a slit in alignment with said crease, said blank also including another portion extending from said upper fold and a display portion extending from said other portion and a cut-out portion extending from said display portion, said other portion being folded back and immovably secured to the back face of said upper fold with said display portion projecting through said slit, said display portion having a crease at its base in alignment with said first crease and the free end of said cut-out portion being immovably secured to the front face of said lower fold, said display portion being caused to assume an upright position when the device is unfolded, said cut-out portion forming a display with said display portion. 80

2. A display folder comprising a blank of sheet material having spaced creases dividing it into upper, central and lower folds and a slit in alignment with the upper crease, said blank also having another portion extending from the uppermost fold and folded back and immovably secured 100 to the rear face of the uppermost fold, said blank also having a display portion extending from one edge of said other portion and projecting through said slit, said blank also having a cut-out tab extending from said display portion, said display 105 portion having a crease at its base in alignment with said upper crease and the free end of said tab being immovably secured to the front face of the central fold, said display portion being caused to assume an upright position when the folder is 110 unfolded, said tab forming a display with said display portion. 115
